Primary Examiner — Rhea Shields(74) *Attorney, Agent, or Firm* — Volpe Koenig(57) **CLAIM**

The ornamental design for a faceplate for a cable tap as shown and described.

DESCRIPTION

FIG. 1 is a top, rear perspective view of a faceplate in accordance with my new design;

FIG. 2 is a top view thereof;

FIG. 3 is a bottom view thereof;

FIG. 4 is a front view thereof;

FIG. 5 is a rear view thereof;

FIG. 6 is a first side view thereof; and,

FIG. 7 is a second side view thereof.

In the drawings, the broken lines are for the purpose of illustrating portions of the faceplate for a cable tap that forms no part of the claimed design.
